ATTYS

UNITED STATES PATENT OFFICE.

DWIGHT C. STURGES, OF MELROSE, MASSACHUSETTS.

BATHTUB ADJUNCT.

Application filed March 3, 1924. Serial No. 696,412.

To all whom it may concern:

Be it known that I, DWIGHT C. STURGES, a citizen of the United States, residing at Melrose, in the county of Middlesex and 5 State of Massachusetts, have invented new and useful Improvements in Bathtub Adjuncts, of which the following is a specification.

The object of the invention is to provide 10 a bath-tub adjunct, comprising a support adapted to rest in an operative position on a bath tub, and an interrupted seat sustained by the support, the form of the support and seat being such that they provide 15 a working space permitting access, without change of position of the body, to body portions which are usually difficult to reach when an ordinary continuous seat is employed, a particular object being to provide 20 a working space which is so accessible from below and at opposite edges of the seat, that a washing instrumentality may be inserted and manipulated either from the front or the back of the body.

25 The accompanying drawing forming a part of this specification, is a perspective view of an adjunct embodying the invention.

The adjunct comprises a support, designated as a whole by 12, and constituting a 30 bridge adapted to span a bath tub, the end portions of the bridge being adapted to rest on opposite edge portions of the tub, and preferably provided with downwardly bent ends, preventing longitudinal displacement 35 of the bridge.

Rigidly secured, as by fastenings 14, to the bridge, is an interrupted seat composed of two seat sections 15, which are so spaced apart by the bridge that a working space 16 40 is provided between said sections.

The bridge is recessed between the seat sections, so that the working space 16 is accessible from points below and at opposite edges of the sections. The bridge is made 45 by bending a stiff metal rod to form parallel

elongated stringers and short necks 13, connecting the end portions of the stringers. The stringers include seat-supporting portions offset downward from the end portions and engaging the fasteners 14, and 50 looped central portions 12^a offset downward from the seat-supporting portions.

A person sitting on the interrupted seat may conveniently wash portions of the body exposed by the working space 16, by inserting 55 a hand in said space, either from the front or the rear of the body.

The described adjunct has only three parts, in addition to the fastenings 14, viz, 60 the elongated bridge and the two seat sections. It is adapted to be used like an ordinary bath-tub seat, and permits more convenient and efficient washing of various parts of the body. The bridge stringers are spaced apart, so that they firmly support 65 the seat sections and prevent the latter from tipping.

I claim:

A bath-tub adjunct comprising a bridge composed of a stiff metal rod bent to form 70 parallel elongated stringers and transverse necks connecting the end portions of the stringers, the stringers including end portions formed to bear on opposite edges of the tub, seat-supporting portions offset 75 downward from the end portions, and looped central portions offset downward from the seat-supporting portions; and an interrupted seat composed of two seat sections, fixed to the seat-supporting portions, spaced apart 80 by the looped central portions and separated from each other and from the looped central portions, by a working space accessible from points below and at opposite edges of the seat sections, the stringers being spaced 85 apart, so that they are adapted to prevent the seat sections from tipping.

In testimony whereof I have affixed my signature.

DWIGHT C. STURGES.
